ROTARY VALVE FOR EXPLOSION ENGINES

Filed Jan. 7, 1928

Inv. No. 2

Jacques Gérin,
by H. B. Willson & Co.

UNITED STATES PATENT OFFICE.

JACQUES GÉRIN, OF PARIS, FRANCE.

ROTARY VALVE FOR EXPLOSION ENGINES.

Application filed January 7, 1928, Serial No. 245,186, and in France January 17, 1927.

The invention has for object to provide an exhaust rotary valve for internal combustion engines and of the known type in which the exhaust gases are allowed to enter a central tube of the rotary valve and to escape from the said tube through a Venturi device in order to suck fresh air between the central tube and the external wall of the valve for cooling the same.

10 In valves of this type provided up to now, the unequal expansion of the external wall, which is the coldest, and of the central tube which is the hottest, produces distortion of the whole and consequently the 15 jamming of the valve in its bearing.

A main object of the invention is to remedy this inconvenience by securing within the valve the central tube in such a manner that the flanges which connect 20 the latter with the ports provided in the said valve have no contact with the same, at their external edge.

The single figure of the accompanying drawing, shows, by way of example only, 25 an axial section of an exhaust rotary valve improved according to the invention.

As above stated the central tube 8^a of the exhaust valve being always sensibly hotter than the outer wall 3^a, a distortion of the 30 latter may result therefrom which is prejudicial to the working; seizures can in fact take place which prevent the free rotation of the valve in its housing in the cylinder head.

35 For avoiding this danger, according to the invention, the central tube 8^a is independent of the flanges 5 leading in the known valves to the ports 38. At its ends, the shape of which is that of the example 40 of the drawing, it is connected by spiders 8^b to sleeves 8^c which fit within the external sleeve 3^a and are secured therein by any suitable means and, for instance, by means of rivets 8^d provided with an external countersunk head. The end of the part 8^a located on the side of the air inlet is closed by a bottom member 8^e secured by a rivet 8^f, or equivalent means. Ports 8^g are provided 45 for increasing the cross section for the admission of air into the annular space 9^a.

A remarkable particularity of this ar-

rangement consists in that the flanges 5 do not touch, by their free end, the sleeve 3^a, so that these flanges, moreover immersed in the cold air stream, cannot act by expansion 55 on the sleeve 3^a always maintained at a relatively low temperature. Furthermore, a clearance *j* is provided between the sleeve 3^a and the inner end of the sleeve 8^c located on the side where issue the exhaust gases. 60 With this arrangement, the end 15 of tube 8^a, always hot, cannot easily transmit its heat, through the ribs 8^b and the rear part of the sleeve 8^c under consideration, to the sleeve 3^a and expand the latter in the region 65 of the clearance *j*.

The construction of the central tube 8^a may be of any kind without departing from the scope of the invention. For instance, use may be made of a steel tube upon which the various elements are secured by autogenous welding, or riveting, or the said parts may be made in one piece of cast metal.

What I claim as my invention and desire to secure by Letters Patent is:

1. In an improved exhaust rotary valve comprising an outer wall or sleeve with exhaust ports and a central tube open at one end for allowing exhaust gases to escape, an outer sleeve open at its two ends, a central tube open at one end which is in the shape of a converging nozzle, external flanges surrounding ports in the said tube, sleeves at each end of the latter and fitting in bearings of the outer sleeve of the valve, spiders for connecting the central tube to the said sleeves in such a manner that the outer edge of the flanges have no contact with the outer sleeve of the valve.

2. In an improved exhaust rotary valve as claimed in claim 1, a bottom member fastened in the air inlet end of the central tube for closing the same and cooled by air passing through orifices provided at the rear part of the said tube, the sleeve which supports the front end of the tube having, in the region of its spiders which connect it with the said tube, no contact with the outer wall or sleeve of the valve.

In testimony whereof I have signed my name to this specification.

JACQUES GÉRIN.
